RAILWAY CAR CONSTRUCTION

James B. Cunningham, St. Louis, Mo., assignor to General Steel Industries, Inc., Granite City, Ill., a corporation of Delaware

Filed Nov. 23, 1964, Ser. No. 413,084

4 Claims. (Cl. 105—420)

The invention relates to railway rolling stock and consists particularly in an improved cushioned underframe structure of the sliding center sill type.

In conventional cushioned underframes of the sliding center sill type, the sliding sill is supported in the underframe a substantial distance inwardly from the end of the underframe, usually at the body bolster, and is not supported outwardly thereof, as at the end sill, principally because any supports outward of the body bolster might interfere with the draft gear mounted in the end of the sliding sill when the sliding sill is in its innermost or full buff position. With the sill thus supported from the underframe substantially inwardly from the end of the sliding sill, after the cushion gear closes and the sill striker engages the stop on the end of the underframe the vertical force which tends to move the struck end of a car downwardly produces a bending moment on the sliding sill which is the product of that vertical force and the arm through which it acts on the center sill; i.e., the distance from its point of application at the end sill to the point of support of the center sill on the underframe, usually at the body bolster. This tends to bend the struck end of the sliding center sill downwardly, and to increase the load on and consequently the frictional resistance of the sliding supports of the center sill at the bolster.

It is accordingly a principal object of the invention to provide a cushioned underframe of the sliding center sill type in which the sliding sill is supported from the underframe at the end sill when fully retracted so as to reduce the bending moment on the sliding sill and provide co-operation between the underframe and the sliding sill in resisting vertical bending moments.

A further object is to provide a sliding sill type cushioned underframe with readily accessible supports for the sliding sill, whereby wear plates thereon may be inspected, removed and replaced without difficulty.

The foregoing and additional more detailed objects and advantages will be apparent from the following description and accompanying drawings, in which:

FIG. 1 is a vertical sectional view of a railway flat car, taken along the longitudinal center line.

FIG. 2 is an enlarged plan view, partially sectionalized, of one end portion of the car illustrated in FIG. 1, taken along line 2—2 of FIG. 4.

FIG. 3 is an enlarged longitudinal vertical sectional view along line 3—3 of FIG. 2.

FIGS. 4, 5 and 6 are transverse vertical sectional views along lines 4—4, 5—5 and 6—6, respectively of FIG. 2.

The underframe comprises a fixed longitudinally extending center sill 1, side sills 3 spaced transversely outwardly of center sill 1 at each side thereof, and end sills 5, body bolsters 7, and cross bearers 9 and 10, all forming rigid connections between center sill 1 and side sills 3, preferably constituting, with the latter parts, a one-piece steel casting. From sill 5 to a point longitudinally outward of body bolster 7, fixed center sill 1 is of hat section, i.e., of inverted channel section with top wall 11 and side walls 13, across the body bolster intersection and to a point longitudinally inwardly therefrom it is of generally box section with a bottom wall 15; longitudinally inwardly thereof it is of the spread type, comprising a pair of transversely spaced generally Z-section members, whose webs are the extended side walls 13, with their up-

2

per flanges 17 mainly directed transversely outwardly and their inner flanges 19 directed transversely inwardly, the latter being a split extension of bottom wall 15. The center sill is of the fish belly type between body bolsters 7, with the depth of side walls 13 increasing from a point intermediate body bolsters 7 and cross bearers 9 to a maximum depth at cross bearers 10, between which their depth is constant. At the bolster intersection bottom wall 15 is formed with a downwardly facing center plate 21 and forwardly and rearwardly thereof with longitudinally spaced pairs of depending transversely extending reinforcing ribs 23. Additional resistance to vertical bending of the sill at the center plate is provided by an inverted longitudinally extending channel 25 on the upper surface of bottom wall 15 between forward and rear reinforcing ribs 23, channel 25 and bottom wall 15 combining to form a strong box section compression member for the sill in this critical region.

End sill 5 is of channel cross section, with upright web 27, and inwardly directed top and bottom flanges 29 and 31, top flange 29 merging with center sill top wall 11. Web 27 is interrupted, except for its upper marginal portion 33 between center sill side walls 13, with which it angularly merges, and is formed with slope sided depending extensions 35 on both sides of the center sill, end sill bottom wall being correspondingly depressed and merging at their inner ends with the depending end portions of center sill side walls 13. To compensate for the center sill opening in the end sill, a cast tie bar 37 of inverted channel cross section, with upwardly facing slope sided pockets adapted to wedgingly receive end sill projections 35 is removably secured by bolts 41 to the latter in wedging engagement therewith, thus forming a compression chord for the end sill.

35 For preventing the direct application of high buffing loads to the underframe and lading, elongated draft sill 43 is slidably received within fixed center sill 1, with its ends protruding from the ends of the latter sufficiently to permit substantial relative longitudinal movement. 40 Draft sill 43 is of the usual A.A.R. hat section, constructed of two rolled Z's, with their webs vertical to form side walls 45 and their upper flanges directed inwardly toward each other and butt welded to each other along their inner abutting edges to form top wall 47, and with their lower flanges 49 directed transversely outwardly.

45 Whereas in conventional cushioned underframes, the draft sill is frequently slidably supported at the bolster-center sill intersection, with the result that inspection, removal, and replacement of supporting wear plates is difficult, if not impossible, according to the present invention the draft sill supporting wear plates are positioned for easy access and increased effectiveness. In order to leave the bottom of draft sill 43 adjacent its ends free and clear for the application of draft gear and coupler supporting plates, keys and the like, the center sill side walls 13, between the bolster and the adjacent end sill terminate above the draft sill flanges 49, and are provided along their lower edges with horizontal double flanges 51, partially overlying, but spaced above the bottom flanges of the draft sill. Flanges 51 mount renewable upwardly facing wear plates 53, and to the outer surfaces of draft sill side walls are secured longitudinally extending angle-section members 55, overlying center sill flanges 51 and provided with downwardly facing renewable wear plates 57 in slidable engagement with upwardly facing wear plates 53.

Additional sliding supports for the draft sill are provided in the spread portion of the center sill, as for example, by means of upstanding bosses 59 on spread center sill flanges 19. Bosses 59 mount renewable upwardly facing wear plates 61 on their upper surfaces and draft sill flanges mount cooperating downwardly facing wear

plates 63 on their lower surfaces in slidable engagement with wear plates 61.

Movements imparted to draft sill 43 by buff and draft forces are cushioned from the underframe, by a cushion device C of any desired type, which may be related to the underframe and draft sill in known manner, to permit their relative movement lengthwise of the car.

The end portions of draft sill 43 are provided with the usual draft lugs 65 forming pockets for draft gear 67, which is surrounded by the usual yoke 69, to which is pivotally attached the shank 71 of coupler 73. A striker casting providing vertical striker surface 75 and coupler carrier pocket 77 forms the coupler mounting mouth of the draft sill, striker surface 75 being engageable with the rear vertical surface of coupler horn 79 to limit movement of the coupler relative to the draft sill resulting from buffing forces.

For limiting movements of draft sill 43 lengthwise of underframe center sill 1, caused by the application of buffing forces to couplers 73, the striker castings are formed with a rearwardly facing sill stop surface 81, which is engageable with the central portion 33 of end sill web 27, surfaces 81 and of end sill web portion 33 both sloping upwardly and inwardly, at an angle of about 60° from the horizontal, lengthwise of the underframe, so that when, under maximum buff load, surfaces 81 and 33 become engaged, and coupler horn 79 engages striker surface 75, the tendency of the buffing load to bend draft sill 43 downwardly will be resisted not only by the draft sill but also by the greater vertical strength of the underframe, due to the underlying engagement of stop surfaces 33 with surface 81. Sloping central web portion 33 is reinforced by a horizontal bottom inwardly directed flange 83, which merges at its ends with center sill side walls 13, and is further reinforced by gussets 85, spread apart transversely and extending lengthwise of the sill, which merge with top wall 11, web portion 33, and flange 83. This will also tend to reduce the load on the draft sill supporting wear plates when the limit of draft sill movement is thus reached, facilitating return to draft sill 43 to its normal centered position lengthwise of the underframe by the usual return spring mechanism which may be incorporated in cushioning device C, but which forms no part of the present invention and is not separately disclosed.

As various changes could be made in the above construction without departing from the scope of the invention it is intended that all matter contained in the above description or shown in the accompanying drawings shall be interpreted as illustrative and not in a limiting sense, and the exclusive use of modifications coming within the scope of the appended claims is accordingly contemplated.

What is claimed is:

1. In a railway vehicle, an underframe, an elongated draft sill, means spaced inwardly from the ends of said underframe and supporting said draft sill in said underframe for movement lengthwise therein with an end portion of said draft sill normally projecting outwardly from the end of said underframe, an end surface of said underframe adjacent said draft sill sloping upwardly and in-

wardly longitudinally of said underframe, said draft sill having a correspondingly sloping surface outwardly of and in opposing normally spaced relation with said underframe surface, said underframe and draft sill surfaces being adapted for engagement when said draft sill moves a predetermined distance lengthwise of said underframe.

2. In a railway vehicle according to claim 1, a coupler mounted in the end portion of said draft sill for movement lengthwise thereof and projecting longitudinally outwardly of the end thereof, said coupler and draft sill having normally spaced apart surfaces in opposing relation lengthwise of the sill and adapted for engagement when said coupler moves inwardly a predetermined distance lengthwise of said sill.

3. In a railway vehicle according to claim 1, said sloping underframe end surface extending over said draft sill, said draft sill mounting a striker casting at its end, said striker casting having a portion extending above said draft sill, said draft sill opposing surface being formed on said upwardly extending portion of said striker casting.

4. In a railway vehicle having a longitudinally extending center sill, said center sill comprising spaced apart sides, separate horizontal wall means spaced apart lengthwise of the vehicle and connecting the bottoms of said center sill sides, a draft sill positioned within said center sill for slidable movement lengthwise thereof, said draft sill having downwardly facing surfaces at each of its sides, upwardly facing surfaces on said center sill sides adapted to underlyingly engage said downwardly facing surfaces, said upwardly facing surfaces being located at points spaced longitudinally of said center sill from said horizontal wall means whereby to facilitate inspection and renewal of said surfaces, said center sill sides having transversely inwardly extending flanges, said upwardly facing surfaces being formed on said flanges, said draft sill having outwardly extending flanges overlying said center sill inwardly extending flanges, said separate horizontal wall means being also spaced from the ends of said center sill to form body bolster bottom walls, said center sill sides terminating above said draft sill flanges in the region between said horizontal wall means and the end of said center sill, with their inwardly extending flanges overlying said draft sill flanges, said draft sill being provided with additional downwardly facing surface forming means on its sides at a higher level than said draft sill flanges for engagement with said inwardly directed center sill flanges.
